UNITED STATES PATENT OFFICE.

LEWIS E. WATERMAN, OF ROCKFORD, ILLINOIS, ASSIGNOR TO EMERSON-BRANTING-HAM COMPANY, OF ROCKFORD, ILLINOIS, A CORPORATION OF ILLINOIS.

CULTIVATOR.

1,391,027.

Specification of Letters Patent. Patented Sept. 20, 1921.

Application filed October 10, 1917. Serial No. 195,684.

To all whom it may concern:

Be it known that I, LEWIS E. WATERMAN, a citizen of the United States, residing at Rockford, in the county of Winnebago and 5 State of Illinois, have invented certain new and useful Improvements in Cultivators, of which the following is a specification.

This invention relates to cultivators, and the primary object is to provide one especially adapted for general cultivating purposes, that is, to meet the conditions and requirements of both field and garden cultivating.

In furtherance of this general object I 15 have incorporated in a cultivator in a novel manner various features of advantage, which enable cultivating in a most practical and efficient manner. Generally stated, these include the provision for shifting the cultivating gangs laterally, simultaneously with the angling or steering of the wheels so as to accurately follow the rows, adjustment of the shovel gangs laterally to accommodate various widths of rows, adjustment of 20 the wheels laterally to narrow or widen the tread, automatic balancing by forward and backward movement of the wheels with respect to the frame when raising or lowering the shovel gangs, and the application of all 25 movements and draft forces in a most simple and direct manner.

By designing to obtain the various adjustments and movements mentioned in a most direct manner, as will be more fully described hereinafter, I am enabled to provide 35 a very simple structure which not only operates effectively and efficiently under all conditions and requirements for general purpose cultivating, but is so constructed that 40 it may be produced for sale at a comparatively low cost.

Among the objects of my invention is a provision, in a pivot-wheel cultivator in which the cultivating gangs are shiftable laterally with angling of the wheels, for 45 mounting the cultivating gangs on a cross shaft or bar or the like which is included in the connection between the wheels for maintaining them in parallelism and which 50 serves to support the cultivating gangs in a rigid and substantial manner and also permits them to be adjusted laterally to accommodate different widths of rows, and for establishing such a connection between the

gang supporting means and wheels that the 55 latter may be moved forwardly and backwardly independently of movement of the gang supporting means, when the gangs are lowered and raised.

Other objects and attendant advantages 60 will be appreciated by those skilled in the art when the invention becomes better understood by reference to the following specification when considered in connection with the accompanying drawings, in which;

Figure 1 is a plan view of a cultivator embodying my improvements;

Fig. 2 is a side elevation of the cultivator with the near wheel removed for clarity of 70 illustration;

Fig. 3 is a view similar to the preceding figure, but showing the cultivating gangs in a raised position and the consequent movement of parts; and

Figs. 4 and 5 are fragmentary front and 75 rear views respectively of one side of the cultivator.

In the present embodiment of my improvements a frame is provided, including spaced side bars 8 and 9, converging forwardly as shown, and pivotally connected at 11 to an interposed tongue 12. A brace bar 13 rigidly binds together and holds in spaced relation the forward portions of the side bars just at the rear of the pole, and the 80 rear ends of the side bars are attached to and secured together by a wheel-arch or axle structure. This, in the present instance, is designed so that the depending portions of the wheel arch may be adjusted laterally for 85 different widths of rows and may be swung forwardly and backwardly for balancing, as will be mentioned hereinafter and consists of a tubular sleeve member 14 secured at its ends by set screws 15 in quadrant brackets 90 95 designated generally by reference character 16, which are shaped to provide forward extensions 17, in which the rear ends of the side bars 9 are seated and rigidly bolted. Telescopically and rotatably mounted with 100 in each end of the sleeve 14 is an elbow wheel-arch member 18 having a depending portion 19 in turn rotatably fitting in a sleeve or axle-supporting bracket designated generally by reference character 21. 105

As noted in Fig. 5, this axle-supporting bracket projects below the lower end of the wheel-arch member and the latter is held

against lengthwise movement upon said portion 19 but is permitted to move rotatably with respect thereto by reason of a pin 22 passing through the member 19 and confined at its ends in slots 23 formed in the sleeve 21. The lower end of each wheel-arch member 19 is stepped upon the upright portion of an elbow axle member 24 which is rigidly secured within the lower end of the bracket 21 by means of a bolt 25. An anti-friction bearing is provided between the axle 24 and wheel-arch portion 19 so that the wheels may be angled freely with practically no frictional resistance of close fitting and binding parts, since the weight of the cultivator is carried entirely through the bracket 21 and pins 22. A carrying wheel 26 is mounted on each axle 24 and a suitable sand box 27 may be employed in connecting the wheel with the axle for preventing sand and foreign matter from entering the wheel bearings. Each wheel-arch member is further held in set position against lateral movement with respect to the frame by a link 28 embracing the portion 19 of its respective wheel-arch just above its bracket 21 and connected by a bolt 29 to the quadrant bracket 16, as shown. These links have each a series of perforations for the reception of fastening bolts 29, so that the wheel-arch members may be adjusted laterally and held in predetermined position by locating the bolts 29 in the desired holes in the links. From the foregoing, it will be noted that a wheel-arch, that is, an arch structure connecting the carrying wheels to the frame, is provided, permitting the wheels to be adjusted laterally to vary the tread and to be moved forwardly and backwardly with respect to the frame and also to be angled about an upright axis for the purpose of steering the cultivator. With reference to these movements, it will be noted that the horizontal portion of each wheel-arch member 18 is telescopically and rotatably fitted in the sleeve member 14 and is held against telescoping movement therein by means of its respective link 28, and that the axle supporting bracket 21, which carries the axle 50 is free to revolve upon the depending portion of its respective wheel-arch member. This gives an exceedingly simple construction, confined strictly to the general shape of the arch structure and while permitting 55 of the various movements just mentioned, is so designed as to be amply strong and durable for withstanding all strains incidental to usage. The means for maintaining the wheel-arch members in upright position and for swinging them backwardly and forwardly and also for angling the wheels, will be described later in connection with the description of the control and operation of the cultivating gangs.

60 It is desirable that the cultivating gangs or

shovel-carrying beams shall be pivotally supported so that they may be easily raised and lowered and shall be shiftable laterally, simultaneously with angling of the wheels, allowing the cultivator to be easily and 70 quickly guided to accurately follow the rows, and shall also be capable of lateral adjustment in accordance with the width of rows and thus be applicable for both field and garden cultivation and shall finally be supported in a rigid and substantial manner, 75 so as to hold to a given and set working relation to the plants, which is especially desirable when close cultivation is desired, as in garden work. With these requirements 80 in view, I have pivotally suspended the cultivating beams or drag bars from a cross bar or shaft, in turn slidable laterally on the frame and connected with the axle supporting brackets, mentioned above, in a manner to establish a steering connection 85 between the wheels, and have provided suitable connections between the shovel beams and cross bar for holding the same in fixed and adjusted relation with respect to lateral movement. This cross bar or shaft 31 is slidably mounted in bearings 32, which are rigidly secured to the side bars adjacent to the front of the cultivator, as shown. The cultivating gangs may be of any suitable 90 or preferred construction, and in the present instance, are of the beam type designed to carry a gang of cultivating shovels on each side of a row of plants. Each gang of shovels is mounted on a beam structure, 95 which, in this instance, consists of a pair of beams 33 having forward upright extensions 34 diverging upwardly and pivotally mounted on the cross bar 31, as shown clearly in Fig. 4. It will be noted that the forward 100 end of each beam structure forms a substantial bracing for the beams so as to hold them rigidly in working position against lateral swinging movement or displacement and that the beams may be adjusted laterally 105 upon and with respect to the rod 31 by reason of the slidable mounting of the beam arms 34 thereupon. An adjustable connection is established between the cross rod 31 and each cultivating gang for the purpose 110 of holding the gangs in fixed relation to the cross rod and also of adjusting the gangs laterally thereupon. This consists of a hand lever 35 pivotally mounted at 36, centrally 115 upon the cross rod and having link connections 37 and 38 on opposite sides of the lever fulcrum, respectively with the two cultivating gangs, a quadrant and latch connection of the usual type being provided for holding the lever fixed in any adjusted position 120 thereof with respect to the cross rod. It will be manifest, therefore, viewing Fig. 1, that by adjusting the lever 35 in a clockwise direction the cultivating gangs will be 125 moved outwardly upon the rod 31 to widen 130

the cultivating paths, and upon moving the lever in the opposite direction the cultivating gangs will be moved closer together.

The means for steering the cultivator, that is, for angling the wheels and simultaneously shifting the cultivating gangs laterally will now be described. It will first be noted that there is a connection between each axle supporting bracket 21 and the adjacent end of the cross rod 31, of such construction as to transmit the lateral movement of the cross rod 31 to the bracket 21 in an oscillating movement by which the wheels will be angled simultaneously with lateral shifting movement of the cross rod 31, and such as will permit the depending wheel-arch members to be swung backwardly and forwardly in the balancing operation of the cultivator, independently of movement of the cross rod, as will be described more fully hereinafter. This connection I have devised in simple form, consisting of a link 39 pivotally connected at its forward end at 41 to a bracket 42 secured to the adjacent end portion of the cross rod 31 and pivotally connected at its rear end at 43 to the upper end of the bracket 21. In this latter connection the bracket is shaped to provide a forwardly opening socket 44 which receives the rear end portion of the link 39 so as to confine the same against sidewise or horizontal movement on its pivot 43, thereby establishing a connection by which the bracket 21 may be oscillated on the depending portion 19 of the wheel arch member, the socket being of a forwardly tapering and enlarging shape, so that the bracket is capable of back and forth swinging movement in a vertical plane with respect to the link 39. Hence, while there is a permanent connection between the cross rod 31 and axle supporting bracket 21 by which the latter will be oscillated to angle the wheels, the bracket 21 is capable at any time of being swung backwardly and forwardly without interfering with the cross rod 21 or its cultivating gangs, for the purpose of balancing the cultivator when the gangs are raised and lowered, as will be mentioned hereinafter. The steering means for moving the cross rod 31 laterally is foot-operated and consists of pendant foot stirrups or levers 45 pivotally mounted on the wheel-arch sleeve 14 and having extended upper arms 46 connected respectively to the adjacent cross rod brackets 42 through the agency of links 47 and 48 and a bell crank 49 interposed between and connected to said links and pivotally mounted on the side bars of the frame to transform forward and backward movement of the arms 46 to a lateral or sidewise movement for moving the cross rod 31 laterally. It will be evident that an operator seated on the saddle 51 carried by the bars 52, in turn secured to

the frame in any suitable manner, may actuate the foot stirrups or levers 45 by forward and backward movement and thereby steer or guide the cultivator in following the rows. The cultivating tools may be guided in very accurate relation to the plants by means of a steering device of the character described.

Hand levers are provided for raising and lowering the cultivating gangs, which it will be noted, may be raised at their rear ends about their pivotal mountings at their forward ends on the cross rod 31. These hand levers 53, one for each cultivating gang, are each pivotally mounted at 54 upon a quadrant bracket 16 and are equipped with the usual spring latch engagement with the notched sector of the quadrant. The levers are extended below their pivots and connected at their lower ends to their respective shovel beams, the connections shown consisting of links 55 having a one-way connection with the beams and equipped with an expansion spring 56, which permits the beams to rise when the shovels encounter any obstruction while passing over irregular ground. By means of this arrangement, when the upper ends of the hand levers 53 are moved downwardly the cultivating gangs will be raised to an elevated position, and in the event that the machine is employed in cultivating between rows of trees in orchards where the limbs of the trees are low, the links 55 may be connected in the holes 57 above the pivots 54 of the levers so that when the tools are in the ground the levers will be in their lowermost position and will not interfere with the limbs of the trees.

By means of a special connection between each cultivating gang and its adjacent carrying-wheel axle or support, the latter will be moved forwardly and backwardly, upon respectively lowering and raising the cultivating gangs, this being for the purpose of automatically balancing the cultivator, as is well known in the art, so that the front end of the pole will not be raised by the change in the center of gravity of the machine incidental to raising the shovels from the ground. For this purpose, each cultivating gang is equipped with a rigidly forwardly and outwardly extending arm 58, which serves also as a draft member, as will be presently mentioned, and the forward end of each of these arms is connected by means of a link 59 to the adjacent sand box bracket at 61 or may be connected to any similar part fixed with respect to the axle. When the gangs are raised they will be swung upwardly and rearwardly about the fulcrum 31 and the wheels will be moved rearwardly about the pivotal mounting of the wheel arches 18, through the agency of the connections 58-59, it being obvious that this movement will

take place entirely independently of any movement of the gang supporting cross bar 31, by reason of the special provision made in the connection between the axle supporting bracket and the cross rod 31.

The draft is applied directly to the members 58, and is consequently applied as immediately and directly as possible to both the wheels and the cultivating tools. This is 10 of material importance, since the draft is not transmitted through any frame structure or complex mechanism, but is applied directly to its point of usage, which makes the cultivator exceedingly light of draft and easy to 15 operate. The draft means illustrated consists of an evener 62 pivotally mounted at 63 on the tongue 12 and equipped at its ends with pendants 64 which are connected intermediate their ends through the agency of 20 clevis links 65 or any suitable means, to the forward ends of the draft members 58, and are adapted to be equipped at their lower ends with whiffle-trees 66. By connecting the draft direct and low to the cultivating 25 gangs, it is utilized to hold the shovels in the ground so that they will be kept scoured and will perform their cultivating function in a very satisfactory manner and will have no tendency to run out of the ground. An 30 adjustable connection is provided between the pole 12 and the frame of the cultivator for relatively adjusting the pole and frame to thereby level the beams or to properly position them with respect to the horizontal 35 in accordance with the work being done. This connection takes the form of an adjustable hand lever 67, pivoted at 68 to a notched segment 69 with which the lever co-operates in the usual way and which is secured to the 40 cultivator frame, and a yieldable link connection 71 between the lever and rear end of the tongue. Referring to Fig. 1, it will be seen that the brackets 42 are shaped to provide a series of openings 40 spaced similarly 45 to the openings in the links 28. These openings 40 enable the links 39 to be properly adjusted when the links 28 are adjusted, as mentioned above, to narrow or widen the cultivator, it being obvious that the bolts 41 50 may be positioned in any opening 40, corresponding with a similar adjustment of the bolts 29, for width.

In the operation of my improved cultivator, it will be understood from the foregoing 55 description that a very sensitive steering device is provided by means of which the cultivating shovels may be very accurately guided with respect to the rows by angling the wheels and simultaneously shifting the 60 cultivating gangs laterally upon operation of the foot stirrups 45; that the cultivating gangs are supported in a very simple and rigid manner, so as to be easily raised and lowered and moved laterally when steering 65 and also so that they may be adjusted later-

ally independent of the steering device to accommodate different widths of rows and to be arranged in the desired proximity to the plants, this being especially desirable in garden cultivation wherein it is necessary 70 that the shovels shall cultivate quite close to the plants; that the draft is applied in a most direct manner to both the wheels and cultivating gangs, thereby insuring lightness of draft and effective operation of the 75 cultivating tools; that there is incorporated in the cultivator among the various other features of adjustment and operation, provision in a simple and novel manner, for effecting automatic balancing of the cultivator 80 when the cultivating gangs are raised and lowered, and that the back and forward movement of the wheels is governed by a direct connection between the same and the cultivating gangs, this balancing feature being accomplished with very little mechanism 85 and without affecting in any way the mounting or positioning of the cultivating gangs, so that with regard to the latter a very simple construction is possible, including the 90 desired adjustments; that the cultivator may be widened and narrowed for field or garden cultivation in a very simple and easy manner; and that the foregoing features are accomplished in a most direct manner by a 95 structure exceedingly simple in view of the many adjustments and desired operating functions of the parts.

It is believed that the foregoing conveys a clear understanding of the principles and 100 operation of my improvements, and it should be understood that while I have illustrated one practical working embodiment thereof, the construction and arrangement of parts 105 might be changed and modified without departing from the spirit and scope of the invention as expressed in the appended claims:

I claim:

1. In a cultivator, the combination of a frame, a wheel arch, a wheel connected with each depending upright portion of the wheel arch in such manner as to be capable of turning about the upright axis thereof and to be movable forwardly and backwardly with respect to the frame about the horizontal axis 110 of said arch, a cross bar mounted upon and slidably laterally with respect to the frame in front of the wheel arch, shovel gangs attached to the cross bar so as to be movable laterally therewith, a connection between 115 each depending portion of the wheel arch and the adjacent end portion of the cross bar for angling the wheels when the cross bar is moved laterally and permitting the wheels to be moved forwardly and backwardly independently of movement of the cross bar, a connection between the shovel gangs and wheels for moving the latter forwardly and backwardly upon lowering and raising the shovel gangs, means for moving 120
2. In a cultivator, the combination of a frame, a wheel arch, a wheel connected with each depending upright portion of the wheel arch in such manner as to be capable of turning about the upright axis thereof and to be movable forwardly and backwardly with respect to the frame about the horizontal axis 125 of said arch, a cross bar mounted upon and slidably laterally with respect to the frame in front of the wheel arch, shovel gangs attached to the cross bar so as to be movable laterally therewith, a connection between each depending portion of the wheel arch and the adjacent end portion of the cross bar for angling the wheels when the cross bar is moved laterally and permitting the wheels to be moved forwardly and backwardly independently of movement of the cross bar, a connection between the shovel gangs and wheels for moving the latter forwardly and backwardly upon lowering and raising the shovel gangs, means for moving 130

the cross bar laterally, and means for raising and lowering the shovel gangs.

2. In a cultivator, the combination of a frame, carrying wheels, wheel-supporting brackets mounted on the frame so as to be revoluble about upright axes and to be movable at their lower ends forwardly and backwardly, carrying wheels attached to said brackets, a cross bar laterally movable upon the frame, shovel beams pivotally attached to the cross bar to swing vertically thereupon, a connection between each wheel-supporting bracket and the adjacent end portion of the cross bar for oscillating the brackets in unison upon lateral movement of the cross bar and permitting back and forth swinging movement of the brackets independently of movement of the cross bar, means for moving the cross bar laterally, connections between the cultivator beams and wheels for moving the latter backwardly and forwardly through the act of raising and lowering the beams, and means for raising and lowering the beams.

25 3. In a cultivator, the combination of a frame, carrying wheels capable of being angled with respect to the line of draft and of being moved forwardly and backwardly with respect to the frame, shovel gangs mounted upon and movable laterally with respect to the frame and having each a forwardly and outwardly projecting extension in substantially the horizontal plane of the beams, means connecting the shovel gang 35 and wheels for angling the latter upon moving the gangs laterally, an evener mounted on the frame and equipped at its ends with depending links, connections between said links and said extensions of the beams and 40 between said beams and the wheel supports, whereby draft applied to said links will be transmitted directly to the beams and wheels, and means for raising and lowering the beams and consequently moving the wheels 45 backwardly and forwardly through the agency of said links between the beam extensions and the wheel supports.

4. In a cultivator, the combination of a frame, a wheel arch mounted thereon, an 50 axle-supporting sleeve bracket revolubly mounted on each depending portion of the wheel arch and held against lengthwise movement thereon, an axle rigidly secured to the lower end of each axle-supporting bracket and equipped with a carrying wheel, laterally movable beam-supporting means mounted on the frame forwardly of the wheel arch, each axle-supporting bracket being shaped at its front side to 55 provide a forwardly opening socket for reception of a link which is confined against sidewise movement with respect to the bracket and is capable of vertical swinging movement relatively thereto, links disposed 60 65 at one end in said sockets and attached to

their respective brackets and connected at their opposite ends to the beam-supporting means, whereby the wheels may be moved forwardly and backwardly independently of movement of said beam-supporting means and whereby also the wheels will be angled upon lateral movement of said means, means for moving the beam supporting means laterally, and means for moving the wheels backwardly and forwardly.

5. In a cultivator, the combination of a frame, a wheel arch having depending portions, an axle-supporting bracket revoluble about each depending portion of the wheel arch and shaped to provide a forwardly opening socket adapted to receive the end of a link in a manner to confine the same against lateral movement with respect to the bracket and to permit the link to swing vertically upon the bracket, an axle secured to the lower end of each axle support, wheels on the axles, beam-supporting means movable laterally upon and with respect to the frame, links disposed at one end in said sockets and connected to their respective brackets and connected at their opposite ends to said beam-supporting means, means for moving the beam-supporting means laterally and consequently angling the wheels, and means for moving the wheels backwardly and forwardly.

6. In a cultivator, the combination of a frame, carrying wheels, mountings for the carrying wheels so that the latter are capable of forward and backward movement with respect to the frame, shovel beams pivotally mounted at their forward ends and equipped adjacent thereto with laterally extending draft members, a link connection between each of said draft members and the wheel mountings so that when the cultivating beams are raised and lowered the wheels will be moved forwardly and backwardly through the agency of said connections, and draft means applied directly to said forward extensions of the cultivating beams.

7. In a cultivator, the combination of a frame, a wheel arch therefor having a depending portion at each side of the frame, an axle-supporting sleeve bracket revoluble upon each of said depending portions of the wheel arch and held against lengthwise movement on said portions, an elbow axle, the upright portion of which is rigidly secured in the lower end of each axle-supporting bracket, the lower end of each depending wheel-arch portion being stepped through the agency of an anti-friction bearing upon the top of said upright axle portion, a wheel mounted on the axle, and means for oscillating the axle-supporting bracket on the depending wheel-arch portion for steering the cultivator.

8. In a cultivator, the combination of a

frame having an upright spindle or the like at each side, an axle-supporting sleeve bracket revoluble about said spindle and projecting below the lower end thereof, 5 means for holding the bracket against lengthwise movement on the spindle, an elbow axle, an upright portion of which is rigidly secured in the lower end of the sleeve bracket, an anti-friction bearing between the adjoining ends of the spindle and axle member, a wheel mounted on the axle, and means for oscillating the bracket on the spindle to steer the cultivator.

9. In a cultivator, the combination of a 15 frame, carrying wheels therefor capable of forward and backward movement for balancing purposes, cultivator beams or drag bars mounted on the frame with capacity for raising and lowering movements and 20 equipped with forwardly extending draft bars, means for raising and lowering the

cultivator beams, draft means connected to the draft bars, and connections between the drag bars and wheels for transmitting forward and backward movement to the latter 25 by the action of lowering and raising the cultivator beams.

10. In a cultivator, the combination of a frame, carrying wheels therefor capable of forward and backward movement with 30 respect to the frame and of pivotal movement about upright axes, a drag-bar support shiftable laterally of the frame, drag bars attached to said support and having forwardly extending draft bars, draft 35 means attached to said draft bars, a connection between each draft bar and the adjacent wheel for moving the latter forward and rearward when the drag bar is lowered and raised, and means for raising and 40 lowering the drag bars.

LEWIS E. WATERMAN.
